UNITED STATES PATENT OFFICE.

GEORGE P. SALISBURY, OF NEW HAVEN, CONNECTICUT, ASSIGNOR TO THE
WINCHESTER REPEATING ARMS COMPANY, OF SAME PLACE.

MACHINE FOR GREASING GUN-WADS.

SPECIFICATION forming part of Letters Patent No. 242,052, dated May 24, 1881.

Application filed February 23, 1881. (No model.)

To all whom it may concern.

Be it known that I, GEORGE P. SALISBURY, of New Haven, in the county of New Haven and State of Connecticut, have invented new 5 Improvements in Machines for Greasing Wads; and I do hereby declare the following, when taken in connection with the accompanying drawings and the letters of reference marked thereon, to be a full, clear, and exact description of the same, and which said drawings constitute part of this specification, and represent, in—

Figure 1, a top or plan view; Fig. 2, a side view; Fig. 3, a sectional view.
15 This invention relates to an improvement in machines or apparatus for applying lubricating material to the edges of gun-wads, commonly called "wad-greasing." The wads to be greased are cut from paper, felt, or other 20 fibrous material, and are such as are commonly used in shot-guns or shot-cartridges, the greasing of the wad being designed for the lubrication of the gun-barrel.

The object of this invention is to automatically apply the grease onto the surface of the wad; and it consists in the mechanism as hereinafter described, and particularly recited in the claims.

A represents a flat disk arranged on a vertical shaft, B, and caused to revolve by the application of power thereto through a pulley, C, on the shaft, or otherwise.

D is a vertical flange, stationary above the disk and standing in close proximity thereto, 35 and within the edge of the disk a little more than the diameter of the wads to be greased. At one point, E, the flange is turned outward in substantially a tangential line, and in a direction opposed to the revolution of the disk, 40 and at this point E a notch is cut in the lower edge of the flange, so as to form a slot, e, between the flange and disk, as seen in partial section, Fig. 2, and so that a mass of wads placed on the disk will be thrown outward 45 against the flange D by centrifugal force until they come to the slot e; then by the same force they will pass out through the slot e into a channel formed by the flange D and guard F outside, as seen in Fig. 1, the wads carried 50 through this channel by the disk on which they rest.

G is a disk arranged on a vertical shaft, H, so as to be revolved in a horizontal plane substantially parallel with the plane of the disk A, revolution being imparted to this disk through a pulley, I, or otherwise, (here represented as a belt from a corresponding pulley on the shaft of the disk A.) The edge of this disk is preferably milled or serrated, as seen at g. On the edge of the disk, both above and below, is a radially-projecting flange, h, the two flanges inclined outward, so as to form an annular groove around the disk wider at its outer edge than at the bottom or periphery proper of the disk.

At one side of the disk G is a corresponding segment, L, distant from the periphery of the disk G the same or little less than the diameter of the wads to be greased, the face of the segment also serrated or vertically grooved, as seen in Fig. 1. This segment also has a flange, l, below and l' above, corresponding to the flanges on the disk G, as seen in Fig. 3. The disk G and its segment L stand in such relation to the disk A, as seen in Figs. 1 and 2, 75 that the wads passing through the channel P by the movement of the disk A are forced successively between the disk G and its segment L, and so that when they enter between the disk G and its segment a rotation is imparted 80 to the wads, so that they roll along the face of the segment, this rotation of the wads being produced in a similar manner to the rotation of bullets in bullet-grooving machines. The serrated edge of the disk or of the segment, or both, prevents the possibility of the 85 wads sliding, and insures the rolling described.

It will be understood that a suitable guide, R, is provided to turn the wads from the channel to pass between the disk and its segment.

Adjacent to the segment a grease-holder, S, is arranged, with an opening, m, onto the upper surface of the segment, gutters n, more or less in number, conducting the grease to all points at the edge of the segment, it being understood that the grease is in a liquid condition, maintained in that condition by heat or otherwise, and so that a constant flow of grease passes over the face of the segment, and so that the wads rolling along the face of the segment will take up the required quantity of grease thus delivered. The surplus grease will

pass off and fall from the lower flange, *l*, on the segment. For the purpose of thus delivering the grease to the working-surface of the segment, the upper flange, *l'*, is arranged to leave an opening, *r*, between it and the segment, as seen in Fig. 3. The wads thus greased pass from between the disk and segment, as seen in Fig. 1, to a suitable receptacle prepared for them. The flanges on the disk and segment prevent the wad from tipping out of its horizontal plane, and because of their inclined surface they prevent the grease from working onto the corresponding surfaces of the wad, which it naturally would do were the surfaces of the flanges parallel with the surface of the wad.

To prevent the wads coming in contact with each other in their passage between the disk *G* and its segment a check is provided, (here represented as a latch-like lever, *T*,) hung upon a pivot, *t*, so that its nose, or a pin projecting from it, stands in the channel leading from the disk *A* to the disk *G*.

On the upper surface of the disk *G* are several studs, 1 2 3, &c., more or less in number, each of which, as the disk revolves, will strike an arm, *U*, on the check *T* and turn it from the channel, as indicated in broken lines, so as to permit a wad to pass the check. Then when the arm *U* falls from the stud which moved it, it falls behind the wad which has passed and in front of the next, thus checking the advance of the column, permitting a single wad only to pass—that is, leaving a space between successive wads—and prevent the possibility of their coming in contact during the operation of greasing.

To maintain a constant and regular flow of grease over the segment *L*, I arrange a reservoir, *W*, with an opening, *w*, the upper edge of which is slightly above the lower edge of the opening *m* in the grease-holder. The reservoir is filled and closed air-tight. The grease will flow out through the passage *w*, air being admitted at the same passage, until the level of the grease in the holder *S* rises so as to close the passage *w*. At that level the grease flows through the passage *m* over the segment, and so fast as the level in the holder falls below the top of the opening *w* in the reservoir more air will be admitted to the reservoir and a corresponding quantity of grease flow therefrom. Thus substantially a constant level of grease is maintained in the holder *S*, and the consequent regular flow therefrom. The flow may be adjusted by raising or lowering the reservoir or adjusting the opening *w* relatively to the opening *m*.

In some cases, as in thick wads, the flanges on the disk and segment may be dispensed with, or the lower flanges only retained; but in general practice I prefer the two flanges on both the disk and segment.

The delivery of the wads to the greasing mechanism may be made by other feeding device than that of the disk *A* operating as de-

scribed. As, for instance, they may be placed upon the disk and guided into the channel—say as by a guide, indicated by broken lines *X*—or they may be otherwise delivered. I however prefer the disk operating through centrifugal force to deliver the wads to the guiding-channel.

The feeding mechanism herein described—that is to say, the horizontally-revolving disk with stationary flange above it, a channel outside said flange and upon the disk, with an opening through said flange through which articles on the disk pass into the channel by centrifugal force produced by the revolution of the disk—may be employed for analogous purposes—that is to say, the delivering of articles into a column for the purpose of feeding them to a device for a subsequent operation.

I am aware of the invention of Hubert R. Allen for greasing bullets, for which he has applied for Letters Patent, in which the bullet rides upon a floor between a revolving disk and a segment, with one or more greasers arranged to grease the surface of bullets revolving between the said disk and segment. I do not claim anything shown or described in said Allen's patent.

I claim—

1. The combination of a revolving disk and a corresponding segment arranged to leave a space between it and said disk, and through which space the wads are caused to roll along the face of the segment, with a grease-holder opening to said segment and delivering a constant flow of grease down over the face of the segment, substantially as described.

2. The combination of a revolving disk and a corresponding segment arranged to leave a space between it and said disk, and through which space the wads are caused to roll along the face of the segment, with a grease-holder opening to said segment and delivering thereto a constant flow of grease, said disk provided with an annular radially-projecting flange or flanges, *h*, on its edge, substantially as described.

3. The combination of a revolving disk and a corresponding segment arranged to leave a space between it and said disk, and through which space the wads are caused to roll along the face of the segment, with a grease-holder opening to said segment and delivering thereto a constant flow of grease, said segment provided with radially-projecting flange or flanges inclined from the face of the segment outward, substantially as described.

4. The combination of a revolving disk and a corresponding segment arranged to leave a space between it and said disk, and through which space the wads are caused to roll along the face of the segment, with a grease-holder provided with opening to said segment and delivering thereto a constant flow of grease, and a grease-reservoir having its delivery-opening in a plane relative to the opening *m* from the grease-holder to the segment, substantially as

described, whereby a constant level or flow of grease is maintained, substantially as described.

5. The combination of a revolving disk and a corresponding segment arranged to leave a space between it and said disk, and through which space the wads are caused to roll along the face of the segment, with a grease-holder provided with opening *m* to said segment and 10 delivering thereto a constant flow of grease; and a mechanism, substantially such as described, to deliver the wads to the space between said disk and segment, substantially as described.
- 15 6. The combination of a revolving disk and a corresponding segment arranged to leave a space between it and said disk, and through which space the wads are caused to roll along the face of the segment, with a grease-holder 20 provided with opening *m* to said segment and

delivering thereto a constant flow of grease, a mechanism, substantially such as described, to deliver the wads to the space between said disk and segment, and a check to prevent the contact of the wads in their passage between said disk and segment, substantially as described. 25

7. The herein-described feed for delivering wads or analogous articles into a column, consisting of a disk revolving in a horizontal plane, a stationary flange above said disk, with an opening through said flange into a channel outside said flange but on the surface of the disk, and through which opening the articles on the disk are caused to pass into said channel by centrifugal force produced by said revolving 30 disk, substantially as described.
